UNITED STATES PATENT OFFICE.

JOHN M. BARR, OF MILWAUKEE, WISCONSIN, ASSIGNOR TO THE LOUIS ALLIS COMPANY, OF MILWAUKEE, WISCONSIN, A CORPORATION OF WISCONSIN.

CONTRACTING APPARATUS.

Application filed November 18, 1922. Serial No. 601,861.

This invention relates to contracting apparatus.

The contracting apparatus is particularly adapted to perimetrically contract the end rings of a rotor winding, although it may be used for various other purposes.

An object of the invention is to provide a contracting apparatus for simultaneously contracting the perimeter of both end rings of a rotor winding.

Another object is to provide a contracting apparatus wherein the carrier and the contracting jaws are integrally formed.

Another object is to provide a contracting apparatus wherein the contracting jaws are yieldingly connected with the carrier member.

Another object is to provide a contracting apparatus wherein the contracting jaws and the carrier member are formed from a single tube.

Another object is to produce an efficient, strong and durable contracting apparatus which may be economically constructed and operated.

Other objects and advantages will hereinafter appear.

The views of the drawings are:

Fig. 1 is an elevation partly in section of the contracting apparatus with a rotor and its winding therein.

Fig. 2 is a plan on line 2-2 of Fig. 1 showing the end ring and the contracting jaws before contraction.

Fig. 3 is a similar view showing the end ring and contracting jaws after contraction.

As illustrated in Fig. 1 there are two sets of contracting apparatus one for each end ring of the rotor winding.

Each set of contracting apparatus, in general, comprises a plurality of circularly disposed jaws 1, an annular carrier 2 therefor, and an annular actuator 3 to surround the jaws and move the same radially toward the center.

As the two sets of contracting apparatus are exactly alike, the upper set only will be described and the lower set will be indi-

cated in the drawings by the same reference numerals with the addition of primes.

The jaws 1 are formed on the inner face of contracting members 4, the outer faces 5 of which are inclined to co-operate with an inclined track 6 formed on the inner face of the annular actuator 3.

The contracting members 4 are integrally and yieldingly connected to the carrier 2 by yielding arms 7.

As illustrated, the carrier 2, contracting members 4 and integral yielding arms 7 are formed from a single metal tube.

After the metal tube has been turned to make it of the proper shape and thickness, then a series of holes 8 are provided inside the carrier 2 and the tube is slotted from each hole 8 to the upper end of the tube thus forming the contracting members 4 and connecting arms 7.

The winding may be applied to the rotor core 9 by inserting the conductors 10 thereof into the rotor slots and joining the ends of the rings 11.

The conductors may be inserted into the rotor slots in the manner shown in my copending applications, Serial Nos. 537,554, filed February 18, 1922, and 605,228, filed December 6, 1922, or in any other desirable manner.

The apparatus described herein is particularly adapted to perimetrically bend or impress the end rings 11 of the winding to hold the conductors 10 thereof within the slots of the rotor.

The rotor with the winding applied thereto is arranged inside the carriers 2 and 2' with a spacing ring 12 therebetween, and the actuators 3 and 3' are placed in position around the contracting members 4 and 4'.

Spacing rings of different lengths may be used to adapt the apparatus for windings of different lengths.

Plugs or mandrels 13 and 14 are provided to limit the extent to which the end rings of the windings are perimetrically contracted.

The plug 13 has an annular shoulder 15 to abut an end of the rotor and space the plug therefrom.

The plug 14 has a similar shoulder 16 to serve the same purpose.

The plug 14 also has a flange 17 on which rests the contracting member 4'.

The lower actuator 3' rests upon a plate 18, and a plate 19 is placed on top of the upper actuator 3.

A centering rod 20 is surrounded by a helical spring 21 which supports the plug 14 and resiliently holds the same in place.

The contracting apparatus with the rotor therein is placed upon the bed plate 22 of a power press and the plunger 23 thereof lowered into contact with the upper plate 19.

Pressure upon the upper plate 19 by means of the plunger 23 causes the actuator 20 and carrier of each set of the contracting apparatus to move axially one toward the other thereby causing the jaws to move inwardly and contract the perimeter of the end rings of the rotor winding.

Before contraction the end rings are of the diameter and occupy the position illustrated in Fig. 2, while after contraction the end rings are of the diameter and occupy the position illustrated in Figure 3.

The helical spring 21 supports the lower plug 14 and allows the plug to move downwardly toward the plate 18 during the contracting operation.

When pressure upon the contracting apparatus is released the stored up energy in the helical spring 21 forces the plug 14 and all parts supported thereby upwardly so that the same may be disassembled more readily.

The invention set forth herein is, of course, susceptible of various modifications and adaptations.

The invention claimed is:

1. Contracting apparatus having in combination an annular carrier, a plurality of circularly disposed contracting members, yielding members integrally connecting the contracting members to the carrier, each contracting member having a jaw on its inner face and having its outer face inclined, and an annular actuator to surround the contracting members and having an inclined track to co-operate with the inclined faces so as to move the jaws inwardly when the carrier and actuator are moved relatively one toward the other.

2. Contracting apparatus comprising a spacing member, a plurality of jaws on either side of said spacing member disposed to form enclosures for an appliance to be contracted, and actuators to surround the jaws and move the same inwardly by relative movement between the jaws and actuators.

3. A machine for contracting the end 65 rings of a rotor winding, comprising a pair of carriers, jaws mounted on said carriers to engage the end rings, and a pair of actuators adapted to actuate said jaws.

4. A machine as defined in claim 3, in 70 which the actuators are in vertical alinement with each other.

5. A machine as defined in claim 3, in 75 which the actuators are relatively movable toward each other.

6. A machine as defined in claim 3, in 80 which the actuators are in vertical alinement with each other, said actuators being relatively movable toward each other.

7. A machine for contracting the end 85 rings for a rotor winding, comprising a pair of carriers, jaws mounted thereon, the jaws on one carrier extending in an opposite direction to the jaws on the other carrier, and actuators adapted to actuate said jaws.

8. A machine as defined in claim 7, in 90 which the jaws have outer inclined faces adapted to be engaged by inclined surfaces on the actuators.

9. A machine as defined in claim 7, in 95 which the jaws are arranged annularly.

10. A machine as defined in claim 7, in 100 which the carriers are mounted on a common support.

11. A machine as defined in claim 7, in 105 which the jaws are arranged annularly and in vertical alinement with the actuators.

12. A machine for contracting the end 110 rings of a rotor winding, comprising an actuator, a tube having longitudinal slits extending from the top of the tube to a point near the bottom, the parts of the tube between the slits serving as contracting members, said contracting members having jaws on their inner faces, their outer faces being adapted to be engaged by said actuator to be actuated by the same.

13. A machine for contracting the end 115 rings of a rotor winding, comprising a carrier, a plurality of contracting members on said carrier and integral therewith, and an actuator adapted to move the contracting members on relative movement between the actuator and the jaws.

14. A machine for contracting the end 120 rings of a rotor winding, comprising a carrier, a plurality of contracting members integrally and yieldingly mounted on said carrier and having jaws on their inner faces to engage the end rings, their outer faces having inclined surfaces, and an actuator having an inclined track to engage said inclined surfaces and to move said jaws into contracted position upon relative movement between said actuator and said jaws.

15. A machine for contracting the end 125 rings of a rotor winding, comprising a carrier, a plurality of contracting members in-

tegrally and yieldingly mounted on said carrier, an actuator to actuate said contracting members, and a resilient support for the rotor.

5 16. A machine for contracting the end rings of a rotor winding, comprising a carrier, contracting members mounted on said

carrier, an actuator to actuate said contracting members, a support for the rotor, and means for limiting the contraction of the 10 end rings.

In witness whereof, I have hereunto subscribed my name.

JOHN M. BARR.
